ABSTRACT

A hermetic compressor unit comprising a hermetic casing containing a compressor including a cylindrical block having an arcuate surface engaging the inner surface of the casing and a suction tube assembly for connecting the compressor to a refrigeration system. The suction tube assembly comprises a steel tubular connector including an end portion extending into an opening in the casing and a sleeve member having a higher ductility than steel that includes a reduced end extending into a suction passage in the block and an enlarged portion engaging the suction tube connector. A steel tubular fitting including an end portion extending into the reduced portion of the sleeve member and a shoulder portion extending into the enlarged portion of the sleeve member that simultaneously compresses the sleeve member in the suction passage and connector to effectively seal the compressor casing and suction tube assembly to the compressor.

FIG.1

FIG.3

FIG.2

HERMETICALLY SEALED COMPRESSOR SUCTION TUBE ASSEMBLY

BACKGROUND OF THE INVENTION

In the manufacture of hermetic compressors for refrigeration systems, it is necessary to provide a fluid tight connector means for connecting the hermetic compressor unit to the refrigeration system.

Until recent years most of the suction tube assembly connectors for connecting a hermetic compressor in a refrigeration system have been composed of copper or aluminum. When using such materials, the usual brazing and soldering techniques have been available for assuring a fluid tight joint between the copper or aluminum conduit and the steel compressor casing during final connection of the compressor to the system. Presently available hermetic compressors such as the one disclosed in U.S. Pat. No. 3,767,334 by Dean C. Rinehart, assigned to General Electric Co., assignee of the present invention, shows a suction tube assembly employing an aluminum conduit joined to the steel casing and a steel tubular fitting including an end portion press fit into the compressor and a shoulder portion engaging the aluminum conduit. When the copper or aluminum suction tube assembly conduits are brazed or soldered to the steel compressor casing, flux is used to protect the joint from oxidation and to remove any oxides which may form during the brazing or soldering procedure. While the use of flux insures an acceptable fluid tight joint at the compressor casing it also creates an additional step in the manufacturing of the hermetic compressor in that the flux and residue caused by the joining procedure must be completely removed from the casing prior to the final sealing of the compressor.

It is therefore an object of the present invention to provide a flux free connecting system that mechanically seals the compressor casing and the suction tube assembly to the compressor.

SUMMARY OF THE INVENTION

The present invention is particularly directed to an improved hermetically sealed compressor unit assembly adapted to assure a fluid tight connection between the compressor cylinder and the suction tube assembly. In accordance with the illustrated embodiment of the invention, there is provided a hermetic compressor unit comprising a steel casing and a compressor including a cylinder or compressor block which may be press fit or heat shrunk into contact with the casing side wall. The block includes a suction passage opening and the casing is provided with a hole aligned with and larger than the suction passage. A tubular steel connector having an end portion extending into the casing hole to a point adjacent the suction passage opening in the block is welded to the casing. A tubular sleeve member having a higher ductility than steel includes a reduced end portion located in the suction passage. A tubular steel fitting having an end portion extends into the sleeve in the suction passage and an enlarged portion extends into the sleeve in the steel connector for simultaneously compressing said sleeve member in the suction passage and connector to seal the casing and suction tube connector to the compressor cylinder block.

BRIEF DESCRIPTION OF THE DRAWINGS

In the accompanying drawings:

FIG. 1 is a horizontal sectional view of a refrigerant compressor unit incorporating the present invention;

FIG. 2 is an enlarged section view taken along line 2-2 of FIG. 1 illustrating the construction of the connector portion of the unit; and

FIG. 3 is a view similar to FIG. 2 illustrating one step in the manufacture of the compressor connector portion.

DESCRIPTION OF THE PREFERRED EMBODIMENT

With reference to FIG. 1 of the drawings, there is illustrated a hermetic rotary compressor unit comprising a cylindrical casing 10 in which there is disposed a rotary compressor 12. The compressor includes a cylinder block 14 having an inner cylindrical surface 16 which in combination with an end plate 18 and the second end plate (not shown) defines a compressor cylinder 20 containing a rotor 22.

The cylinder block 12 includes diametrically opposed legs or extensions 24 having arcuate surfaces 26 engaging the inner surface of the cylindrical casing wall 10. In the manufacture of such compressors, the cylinder block may be either pressed into the casing or the casing heat shrunk onto the cylinder block.

A suction passage 28 extends through the cylinder block from one of the arcuate surfaces 26 and into the compressor cylinder 20. The outer end of this passage, as illustrated in FIGS. 2 and 3 of the drawings, is in axial alignment with a flanged hole 30 in the casing side wall 10. The hole 30 has a somewhat larger diameter than the passage 28. A compressor of this general construction is shown in U.S. Pat. No. 3,568,712-Rinehart, to which reference is made for a more detailed description of its construction and operation.

In accordance with the present invention means are provided for connecting the suction line of a refrigeration system to the suction passage 28. To this end in one embodiment of the invention, as shown in FIGS. 2 and 3, there is provided a suction tube assembly 32 which comprises a tubular steel connector or conduit 34 secured to the compressor casing 10, a tubular sleeve member 36 and a tubular steel fitting 38. The steel connector 34 has a reduced end portion 40 extending into or through the hole 30 to a point adjacent the arcuate surface 26 of the compressor cylinder block 14. The end portion 40 is preferably of frustum configuration that permits the end portion 40 of the connector 34 to project into the hole 30 and facilitate alignment of the connector 34 relative to the hole 30 and passageway 28. The end portion 40 of the connector 34 is welded to the casing 10 at the flange portion of the hole 30 as indicated at 42 to form a fluid tight seal between the casing 10 and the connector 34. In the present embodiment, the opening 37 of the connector 34 adjacent the surface 26 has a diameter smaller than the main tubular body portion of the connector 34 but larger than the passageway 28 in the cylinder 14. The tubular sleeve member 36 has been chosen from the group of metals having a higher ductility than steel. While in the present embodiment aluminum is used to fabricate member 36, it should be understood that other ductile materials relative to steel may be employed. The aluminum member 36 has a reduced end portion 44 which extends into the cylinder passage 28 and an enlarged portion 46 extending into the connector 34 adjacent the opening 37. The tubular steel fitting 38 is then employed to me-

chanically connect the connector 34 to the passage 28. Referring to FIG. 3 the tubular fitting 38 is inserted through the connector 34 and into the aluminum sleeve 36 to the position shown in FIG. 2. Fitting 38 includes a reduced end portion 48 which is press fit into the end portion 44 of sleeve 36 in the passage area 28 and a shoulder or enlarged portion 50 press fit into portion 46 of the sleeve 36 that is located in the opening 37 of the connector 34. In effect, the tubular steel fitting 38 simultaneously compresses the aluminum sleeve member 36 in two areas or critical points; namely, area A in the passageway 28 and area B in the opening 37 of connector 34. The liquid tight seal provided at points A and B are effective to mechanically seal the compressor casing 10 and suction tube assembly to the compressor 12.

It should be noted that the use of a ductile sleeve member 36 allows greater tolerance flexibility. This is especially true in the passage area where steel to cast iron seals are possible due to the presence of graphite in the cast iron. However, they require extremely close tolerances and as a result create manufacturing difficulties.

Means are also provided in the present embodiment of the invention to prevent galling of the relatively soft sleeve 36 in areas A and B by the steel fitting 38 that may result in the introduction of foreign particles into the hermetic compressor. To this end the leading edge of fitting 38 is tapered so that the sleeve 36 in area A is compressed by a wedging action as fitting 38 is forced into place. The leading edge of the enlarged portion 50 is provided with a radius which minimizes the possibility of galling in area B. In the event galling does occur in area B, it will be contained in a catch or receiving area 52 that is defined partially by a circumferentially disposed groove formed in the fitting 38.

For assembly to the suction line 54 of a refrigeration system, the end of the line 54 is slip fit onto the connector 34 and adhesively bonded thereto by use of a suitable adhesive such as an epoxy cement. The use of a steel connector 34 permits the use of a welding procedure in attaching the connector 34 to the steel casing 10 that is relatively inexpensive and provides a reliable fluid tight seal. Further, the use of a steel connector 34

provides a compressor that is adaptable for use with either an aluminum or copper refrigeration system in that the adhesive joint is compatible with both systems.

While there has been shown and described a specific embodiment of the invention, it will be understood that it is not limited thereto and it is intended by the appended claims to cover all such modifications as fall within the true spirit and scope of the invention.

I claim:

1. A hermetic compressor unit comprising:
a casing including a side wall;
a compressor including a cylinder block positioned in said casing and having an outer surface adjacent the inner surface of said casing wall;
a passage in said block opening into said outer surface;
said casing having an opening aligned with and larger than said passage;
a suction tube connector including an end portion extending into said opening in axial alignment with said suction passage, and having an opening larger than said passage;
a tubular sleeve member being of greater ductility than the suction tube connector, the sleeve having a reduced end portion extending into said passage and an enlarged portion extending into the end portion of said suction tube connector; and
a tubular fitting having an end portion extending into said reduced end portion of said sleeve member and a shoulder portion extending into said enlarged portion of said sleeve member to simultaneously radially compress said sleeve member in said passageway and said end portion of said suction tube connector to seal the casing and suction tube connector to the compressor cylinder block.

2. A compressor according to claim 1 wherein said suction tube connector and said tubular fitting is steel, and said tubular sleeve member is aluminum.

3. A compressor according to claim 1 wherein a circumferentially disposed receiving area is provided adjacent said shoulder portion of said fitting to entrap foreign matter that may be caused by the compression action of said shoulder portion on said sleeve.
